PROCESS OF REMOVING COLLOIDAL SUS-
PENSIONS FROM VEGETABLE OILSRalph H. Fash, Fort Worth, Tex., assignor to
Anderson, Clayton & Co., a joint-stock associa-
tion, Houston, Tex.No Drawing. Application October 13, 1938,
Serial No. 234,841

4 Claims. (Cl. 260—422)

This invention relates to the removal of colloidal suspensions from non-aqueous liquids. The invention is especially suitable for the refining of non-aqueous substances such as oils, 5 and, as illustrating one important application of the process, the removal of coloring matter from vegetable oils, as for example, cotton seed, soya bean, and peanut oils, will be described.

In refining vegetable oils, the present practice 10 is to add a large excess of caustic alkali for the purpose of neutralizing the free fatty acids present in the crude product, and to substantially reduce the color of the oil and remove undesirable constituents. The soap stock, together with the 15 coloring matter, are then separated from the oil by settling or by centrifuging, or in any other conventional manner. Frequently, the reduction in color of the oil resulting from a single refining operation is insufficient and it has been the practice to re-refine the oil in a similar manner one 20 or more times. In many instances, the color cannot be reduced to the desired point without excessive refining losses due to the reaction of the alkali with the oil to form soap.

25 As a result of extensive investigation, I have ascertained that the coloring matter in the oil is present as an electrically charged colloidal suspension.

While it was formerly believed that the removal 30 of the coloring matter by the caustic alkali was due to the solvent effect of the latter, a more acceptable theoretical explanation of the removal of the coloring matter is based on the hypothesis that the colloidal coloring matter is electrically charged, and, in the treatment of the oil with 35 alkali colloidal soap is formed, which soap colloid, being negatively charged, tends to neutralize the colloidal material which is positively charged.

As described in my copending application Se- 40 rial No. 234,840, filed October 18, 1938, I have discovered that a greater reduction in color with less refining loss can be obtained by utilizing a highly dispersed negatively charged colloid, thus 45 overcoming the relative inefficiency of the present practices, which is due to the fact that the soap colloid which is formed is not highly dispersed and does not as satisfactorily bring about electrical neutralization and precipitation of the colloidal material which is to be removed.

50 While the invention described in my copending application above referred to, is concerned with the utilization of a more highly dispersed colloid which will act upon the colloidal material to be removed, the present invention, on the other hand, relates to a method of refining whereby

the state of dispersion of the colloidal material which is to be removed is changed so as to render it capable of being acted upon more efficiently by any other colloid which may be used in the refining process.

5 It has now been ascertained that the colloidal coloring matter is present in the oil in various states of dispersion, and that which remains in the oil after one or more refining operations is that which is the most highly dispersed. While 10 the major portion of the colloidal material is removed in the first refining operation, even where the ordinary soap colloid is the removing agent, great difficulty is experienced in removing the very highly dispersed colloidal material which 15 remains in the oil after one or more refining operations, due to the extremely high dispersion of the colloid.

I have found that the dispersion of the colloidal material which is to be removed can be 20 substantially reduced by exposing the oil, preferably after a preliminary refining operation, to the action of radiant energy. The radiant energy tends to agglomerate the colloidal material which is to be removed and render it capable of being 25 acted upon by the colloid which is used in a subsequent refining operation.

It has long been known that oil may be bleached 30 by the action of sunlight or ultra-violet light, but this bleaching effect is temporary and the color will return.

Since the true effect of the sunlight or ultra- 35 violet rays was not appreciated, the treatment with radiant energy is not at the present time regarded as being of value in the production of a permanently bleached oil. However, I have found that if the oil which has thus been acted upon is re-refined either by the conventional alkali treatment or any other refining treatment 40 which utilizes colloids, before the colloidal coloring matter has had an opportunity to become re-dispersed, a very substantial and permanent reduction in color is obtained.

The radiant energy which I prefer to use is 45 that which has a shorter wave length than yellow light, or in other words, having a wave length less than 0.535 micron. The action of yellow light is neutral in this respect, and the action of rays having a longer wave length, as for example, red rays, increases the stability of the suspension. 50 It is therefore desirable, particularly when using sunlight, to filter out the rays having a wave length longer than 0.535 micron. It will, therefore, be understood that by the term "radiant energy" as used in the specification and in the 55

appended claims, I refer to radiant energy having a wave length less than 0.535 micron.

It has also been found that the shorter the wave length of the radiant energy which is used, the better the results which are obtained.

The following examples are illustrative of the preferred procedure: In all of these examples, an oil which had been refined to a color of 35 yellow, 13.2 red was used.

- 10 A small quantity of 13.2 red oil was placed in a Pyrex dish, the depth of the oil being eleven-sixteenths of an inch. A 445-610 watt Cooper-Hewitt lamp was directed at the exposed surface of the oil at a distance of three and one-half inches, and the oil was exposed to the ultra-violet rays for ten minutes. During the exposure, the oil was agitated with a stirring rod. Within an hour, the oil was re-refined and the color was reduced to 35 yellow, 9.8 red.
- 20 A second experiment was carried out, starting with another sample of the 13.2 red oil having a depth in the dish of about one-sixteenth of an inch, and the time of exposure was reduced to five minutes. There was thus produced an oil 25 which upon re-refining possessed a color of 9.5 red.

The above results are to be compared with the results obtained by re-refining a sample of the same 13.2 red oil without exposure to radiant energy, which gave a color of 35 yellow, 10.3 red.

As illustrating the effect of X-rays, a small quantity of 35 yellow, 12.4 red refined oil having a depth of approximately one-half inch, was exposed for ten minutes at a distance of four and one-quarter inches to the action of X-rays. The total Roentgen units used in the ten minutes was 5850. Within an hour, this oil was re-refined and the color was reduced to 35 yellow, 8.3 red.

The results produced by the use of the X-rays 40 are to be compared with the fact that the same oil re-refined without exposure to radiant energy gave a color of approximately 10.3.

In commercial practice, the oil may be more efficiently treated by subjecting the oil, in the form of a thin film or spray, to the influence of the radiant energy.

It will be apparent that other rays having 5 various wave lengths less than 0.535 micron may also be used, and the invention is not to be regarded as limited by the foregoing examples.

I claim:

1. The process of refining vegetable oil which 10 consists in removing a large proportion of colloidal material, subjecting the oil to the action of radiant energy having a wave length of less than 0.535 micron to reduce the dispersion of the remaining colloidal material and removing 15 the colloidal material, the dispersion of which has been reduced.

2. The process of refining vegetable oil which 20 consists in subjecting the oil to a preliminary refining operation, then subjecting the oil to the action of radiant energy having a wave length less than that of yellow light to reduce the dispersion of the remaining colloidal material and removing 25 the colloidal material, the dispersion of which has been reduced.

3. The process of refining vegetable oil which 30 consists in removing a large proportion of colloidal material, subjecting the oil to the action of ultra-violet rays to reduce the dispersion of the remaining colloidal material and removing 35 the colloidal material, the dispersion of which has been reduced.

4. The process of refining vegetable oil which 35 consists in removing a large proportion of colloidal material, subjecting the oil to the action of X-rays to reduce the dispersion of the remaining colloidal material and removing the colloidal material, the dispersion of which has been reduced.

RALPH H. FASH.
